UNITED STATES PATENT OFFICE.

JOHN CUTHBERT, OF CHICAGO, ILLINOIS, ASSIGNOR TO JOHN CUTHBERT COMPANY, OF CHICAGO, ILLINOIS, A CORPORATION.

PANEL-BOARD.

1,360,372.

Specification of Letters Patent. Patented Nov. 30, 1920.

Application filed October 12, 1915, Serial No. 55,402. Renewed May 3, 1920. Serial No. 378,651.

To all whom it may concern:

Be it known that I, JOHN CUTHBERT, a citizen of the United States, residing at Chicago, in the county of Cook and State of Illinois, have invented certain new and useful Improvements in Panel-Boards, of which the following is a specification.

My invention relates to improvements in panel boards for electric distribution circuits and has especial reference to composite boards of this character to be made up of a plurality of like sections or units and to the arrangement of the parts and to the character of the units.

Some of the objects of my invention are to provide an improved panel board unit more compact in its organization; more easily assembled and installed; cheaper in cost of construction, than are devices of like character heretofore known and generally used and which has all of its energizable parts entirely covered and protected by an overlying removable cover of insulating material.

Another object of my invention is to provide a panel board unit, of the character described, with a double-pole snap switch in a branch circuit thereof, the base of which is an integral part of the unit base.

Another object of my invention is to provide insulating supporting means to raise the insulating body, upon which the metal or electrical conducting portions of the unit are mounted, above the wall or board upon which the unit is to be secured, to provide wire receiving recesses thereunder, which recesses are parallel with the bus bars to which the units, of the component board, are to be connected.

Other and further objects of my invention will become readily apparent to persons skilled in the art, from a consideration of the following description when taken in conjunction with the drawings, wherein:—

Figure 1 is a plan view of the panel, showing parts with the insulating cover removed.

Fig. 2 is a transverse section taken on line 2—2 of Fig. 1.

Figs. 3 and 4 are details of the switch construction.

Fig. 5 is a longitudinal section, taken on line 5—5 of Fig. 1.

Fig. 6 is a transverse section, taken on line 6—6 of Fig. 1.

Fig. 7 is a section taken on line 7—7 of 55 Fig. 1.

In all the views the same reference characters are employed to indicate similar parts.

The insulating body or base portion of the device, or the porcelain block 10 in the particular exemplification, extends the full length and width of the unit, and when the unit is intended for a three wire system of distribution it is provided with three transversely extending grooves 11, 12 and 13, for 60 parallel bus bars, 14, 15 and 16, respectively. Between the bus bars 14 and 15 are depressions 17 and 18 for fuse receptacles 19 and 20, respectively, and between the bars 15 and 16 are similar depressions for receptacles 21 and 22, respectively. These receptacles are of the usual screw shell construction, having a shell 23 and a central contact 24. The receptacles 18 and 19 are for one branch circuit, controlled by the snap 70 switch 25. The receptacles 21 and 22 are for another branch circuit controlled by the switch 26. The switches 25 and 26 are of usual form and substantial duplicates and the receptacles on the one side of the neutral 75 bus bar 15 and their connections, are substantially duplicated by those on the other side, the unit thus providing for two branch circuits, each having a controlling snap switch beyond the fuse plug. 80

In constructing my unit for two wire circuits, only one of the bus bars, on either side of the otherwise designated neutral bar 15, and the respective fuse plug receptacles and switch are all that will be necessary, the unit 90 being correspondingly shorter, or without modification the bus bars 14 and 16 may be connected as a common terminal for one side of a two wire circuit, and the bar 15 may be connected to the other side. 95

Each of the fuse plug receptacles is provided with a relatively long angular connector 27 secured to the central contact screw 24 by the nut 24' and extending through a depression or recess 28 in the bottom surface 100 of the block 10 and vertically as at 27' in a similar depression, substantially equal to the width and thickness of the connector 27 and terminating with a forwardly extending lip 29, which serves as a switch blade for the switch 25 or 26. The lips 29 extend toward the switches, on each side of the unit, for coöperation with the movable walking-

beam switch lever 30 operable by the push buttons 31 and 32. Each of the fuse receptacles is also provided with an angular connector 33. The upturned portion of the 5 connector 33 rests upon the flange 23' of the shell 23, being bored rather large so as to clear the screw 24, as at 34, and being held in contact with the flange 23' by means of the central contact screw. The upturned 10 portion of the connector 33 is connected to a bus bar, 14, 15 or 16, as the case may be, by means of a screw 35, taking through the bar and through a similar connector on the opposite side of the bar when two connectors, one on each side, are connected with the neutral or central bus bar. The connector 33, of the associate receptacles is then 15 connected to the opposite plus and minus bus bars. The receptacle 19 has its connector 33 connected with the bus bar 14, while the associate receptacle 18 has its connector 33 connected to the neutral bus bar 15, and in like manner the connectors 21 and 22 are 20 connected to the respective bus bars. A terminal plate 36, for the switches 25 and 26, is secured in a depression in the block 10 and held in place by a screw 37. The plate 36 is provided with a downturned lip 39 serving 25 as a switch blade for coöperation with the switch lever 30 and the lip 29. The plate 36 is perforated, as at 40, for insertion of a branch circuit wire 41 and the terminal binding screw 42, preferably such as disclosed in my copending application, Serial 30 No. 35,064, filed June 19th, 1915, and which perforation registers with a recess 43 made in the block 10, whereby the wire may be inserted into proper relation with the binding screw 42, by which it may be coiled 35 around the shank thereof, and thereby held firmly in contact with the plate 36, which is an integral part of the switch blade lip 39. To provide for a larger number of branch 40 circuits than two, it is only necessary to add another switch unit, substantially as shown in Fig. 1, and connect the same to the bus bars 14, 15 and 16, in the same manner as the said unit is shown to be connected thereto. Provision can thus be made for 45 any desired number of branch circuits on a given panel.

The units for a given size panel are connected to a board or plate preferably a steel plate 45, by means of screws 46, of which 50 there may be two or more, one at each end of each unit, as shown in Fig. 1.

All of the conducting parts of the entire unit may be inclosed by a cover 48 perforated for the fuse plug 49 and for the 55 switch push buttons 31 and 32.

The cover has preferably downturned end flanges 49 and 50. These flanges rest upon the upper surface of the block 10. The cover 48 is also preferably provided with 60 three parallel flanges 51, 52 and 53 that lie

in the grooves 11, 12 and 13, respectively. The cover 48 incloses all of the energizable parts of the unit and may be held in place by means of screws 54, of which there may be any required number, or by other means. 70 It has perforations registering with the receptacles 18-21 and with the switch buttons 31 and 32.

The body part of the porcelain block 10 is held in elevated position by means of integral posts 56, 57 through which attaching screws may pass, as shown, and side posts 58 and 59, thereby to provide wire receiving channels under the receptacles of the unit and between the posts 58 and 59 and the 80 downward end projections 60 and 61, of the unit.

It is manifest that switches other than push button switches may be employed in the construction of my unit and other fuse 85 receptacles may be used without material change and it is equally apparent that the units may be designed and used for a two wire distribution system, instead of a three wire system, as shown, in which event only 90 one switch, either switch 25 or 26 will be employed and only two bus bars, either 14 or 16 in connection with the central bus bar 15 would be necessary and it furthermore may be understood that other changes in the 95 arrangement and disposition and general configuration of the parts may be made within the scope of the appended claims and without departing from the spirit of my invention.

Having described my invention, what I 100 claim is:

1. A branch-circuit panel-unit comprising a base block grooved to receive three bus bars; a fuse receptacle in said block, below 105 its face and between adjacent grooves; a switch for connection with said fuse receptacle having operating means extending upwardly therefrom; branch circuit terminals connected to said switch; and a removable 110 insulating cover overlying said fuse grooves, bus-bar receptacle, switch and branch circuit terminals and having perforations registering with said fuse receptacle and another perforation to receive said switch operating 115 means whereby to insulate and protect all conducting parts of the unit from contact therewith.

2. A branch-circuit panel unit comprising a base block having grooves to receive a 120 plurality of bus-bars below its face; a plurality of fuse receptacles in said block below its face and between adjacent grooves; a switch for connection with each pair of 125 fuse receptacles, each switch having operating means extending upwardly therefrom; branch circuit terminals mounted on said block and a removable, insulating cover overlying said fuse receptacles, bus bar grooves switches and branch-circuit termi- 130

nals and having perforations registering with the fuse receptacles, whereby to insert the fuses without removing the cover, and other perforations to receive the switch-operating means.

3. In a branch circuit panel unit a base having three parallel spaced-apart transversely extending grooves within which to receive bus bars and two switch receiving 10 extensions; one beyond each of the outside grooves; two pairs of depressions within which to receive lamp holding conductors, said depressions located between adjacent grooves so as to position a bus bar on each 15 side of each receptacle.

4. In a branch circuit panel unit, a base having three parallel spaced apart transversely extending grooves within which to receive bus bars and two switch-receiving 20 extensions, one beyond each of the outside grooves; two pairs of depressions, within which to receive lamp-holding conductors, said depressions located between adjacent 25 grooves so as to position a bus bar on each side of each receptacle and a suitably per-

forated cover of insulating material for overlying the top surface of the base and extending down the ends thereof.

5. In a branch circuit panel unit, a base having three parallel spaced apart transversely extending grooves within which to receive bus bars and two switch receiving extensions, one beyond each of the outside grooves; two pairs of depressions, within which to receive lamp holding conductors, 30 said depressions located between adjacent grooves so as to position a bus bar on each side of each receptacle, said base having perforations extending from its vertical surface to its horizontal surface, at its ends, through 35 which to insert branch wires for connection to the switches.

In testimony whereof I hereunto set my hand in the presence of two subscribing witnesses.

JOHN CUTHBERT.

In the presence of—
MARY F. ALLEN,
FORÉE BAIN.
